UNITED STATES PATENT OFFICE.

LEON C. SCHONEMAN, OF NEW YORK, N. Y.

DESIGN FOR A RECEPTACLE.

SPECIFICATION forming part of Design No. 34,498, dated May 14, 1901.

Application filed April 2, 1901. Serial No. 54,091. Term of patent 14 years.

To all whom it may concern:

Be it known that I, LEON C. SCHONEMAN, a citizen of the United States, residing at New York, in the borough of Manhattan and State 5 of New York, have invented a certain new and original Design for Receptacles; and I do hereby declare the following to be a full, clear, and exact description of the invention, such as will enable others skilled in the art to which 10 it appertains to make and use the same.

My invention relates to a new and original design for receptacles.

In the accompanying drawings, Figure 1 is a perspective view of my receptacle, and Fig. 15 2 is a top view thereof.

20 a represents the body of the receptacle, perforated at b. The body of the receptacle is elliptical in shape and is provided with a bottom c, which is perforated at d. The rear of the receptacle is extended upward to a considerable distance, forming a back e, which back is cut on each side of the central portion, this central portion f being bent downward, leaving an approximately cylindrical portion g, by which the receptacle may be attached to any desired holder. When this central portion is bent down, it of course leaves two projecting portions h and i. The lower corners of these projecting portions are bent upwardly, as indicated at j and k, forming channels directed toward each other.

Having thus described my invention, what I claim as new, and desire to secure by Letters Patent of the United States, is—35 The design for a receptacle as herein shown and described.

In testimony whereof I affix my signature in presence of two witnesses.

LEON C. SCHONEMAN.
